[57] CLAIM

The ornamental design for a corner bracket for picture frame or the like, as shown and described.

DESCRIPTION

FIG. 1 is a perspective view of a corner bracket for picture frame or the like showing my new design;
FIG. 2 is a front elevation view of the corner bracket of FIG. 1;

FIG. 3 is an end elevation view taken from the right-hand end of FIG. 1;

FIG. 4 is a rear elevation view of the corner bracket of FIG. 1;

FIG. 5 is a top plan view of the corner bracket of FIG.

1, it being understood that an end elevation view taken from the right-hand end of FIG. 1 would have a similar appearance;

FIG. 6 is a bottom plan view of the corner bracket of FIG. 1;

FIG. 7 is a perspective view of an alternate embodiment of a corner bracket in accordance with my new design therefor;

FIG. 8 is a front elevation view of the corner bracket of FIG. 7;

FIG. 9 is an end elevation view taken from the right-hand end of FIG. 7;

FIG. 10 is a rear elevation view of the corner bracket of FIG. 7;

FIG. 11 is a top plan view of the corner bracket of FIG. 7, it being understood that an end elevation view taken from the right-hand end of FIG. 7 would have a similar appearance;

FIG. 12 is a bottom plan view of the corner bracket of FIG. 7;

FIG. 13 is a perspective view of yet another embodiment of a corner bracket in accordance with my design therefor;

FIG. 14 is a front elevation view of the corner bracket of FIG. 13;

FIG. 15 is an end elevation view taken from the right-hand end of FIG. 13;

FIG. 16 is a rear elevation view of the corner bracket of FIG. 13;

FIG. 17 is a top plan view of the corner bracket of FIG. 13, it being understood that an end elevation view taken from the right-hand end of FIG. 13 would have a similar appearance; and

FIG. 18 is a bottom plan view of the corner bracket of FIG. 13.
